WINDING MACHINE

Dickerson G. Baker, Holyoke, and Dwight R. Gardner, Springfield, Mass., assignors to The American Thread Company, New York, N. Y., a corporation of New Jersey

Application June 6, 1935, Serial No. 25,206

40 Claims. (Cl. 242—35.5)

The present invention relates to winding machines, and has special reference to machines for winding thread cops with "Universal" or "Fiji" wind.

- 5 One of the objects of the invention is to provide a machine of this character which is capable of high speed operation, and requires a minimum amount of care and attention on the part of the operator.
- 10 Other of the objects of the present invention are to provide novel and improved mechanisms for starting the wind, fastening the thread, delivering cop cores to the machine, and doffing completely wound cops, and knockoff, yardage measuring and other mechanisms which jointly contribute to the efficiency of the multi-spindle automatic machine illustrated in the drawings. It will be apparent, however, that certain of such mechanisms are capable of separate use in single spindle and other types of winding machines.

25 The several features of the invention, whereby the above mentioned and other objects may be attained, will be understood from the following description and accompanying drawings, in 25 which:

Figure 1 is a plan view of a machine, certain parts broken away, embodying features of my invention in their preferred form;

Fig. 2 is a sectional view taken on the line 2—2 30 of Fig. 6;

Fig. 3 is a sectional view, partly in elevation, taken substantially on the line 3—3 of Fig. 1;

Fig. 4 is a detail sectional view, on an enlarged scale, taken on the line 4—4 of Fig. 3;

Figs. 59 and 60 are sections on the lines 59—59 and 60—60 of Fig. 58.

The machine illustrated in the drawings is particularly adapted for use in the manufacture of thread cops or bobbins for the shuttles of sewing machines of the form of the one shown in Figure 53. This bobbin comprises a tubular core 2 which may be of paper, and a mass of thread 4 cross wound on the core, preferably by means of a Universal or Fiji wind. The outer end of the thread is fastened by means of a loop 6 formed therein which is tucked a distance beneath one of the outer layers of thread.

As shown, the machine is provided with a series of twelve winding heads that are carried by an intermittently rotating turret 8 (Figs. 1 and 3). Each of the winding heads comprises a winding spindle 10, a rotary thread traverse guide 12, and a bridge 13.

At the completion of each intermittent movement of the turret, a winding head is moved to a station A where a cop tube or core 2 is placed on the end of the winding spindle 10 (Fig. 11), and secured in position. Such delivery of the cop core to the spindle is effected by means of a device 14 which removes a core from a magazine tube 16 and positions it on the end of the spindle against a shoulder 17 on the spindle tip. The spindle tip is then expanded to securely hold the core on the spindle tip and against said shoulder.

The next movement of the turret positions the spindle with the cop core secured thereon at a station B where the end of the thread associated with the winding head is applied to the core and the winding of the thread on the core is started.

Previously to the application of the thread to

the cop core and the starting of the wind, the end of the thread extending from the thread traverse guide 12 is held by a spring clip 18 (Figs. 18 and 26). As the winding head reaches said second-mentioned station B, gripping jaws 20 grip the thread beneath the clip 18 and pull the thread upwardly and over the cop core that is on the spindle (Fig. 28). Thread retaining fingers 22 are then advanced and closed on the core. The upper finger 22 engages the top of the core 10 in a predetermined position, and is of sufficient length to extend over the thread and thus clamp the thread to the core. The gripping jaws 20 then open so as to release the end of the thread and are retracted therefrom.

With the thread thus held by the retaining finger 22 on the cop core, the spindle is rotated so as to wind the thread on the core a number of turns to start the wind. During this initial winding of the thread the retaining fingers 22 are rotated with the spindle and core so that a number of turns of thread are wound on the core and over the longer retaining finger 22. In order to insure that the loose end of the thread shall lay properly on the core so as not to project from the ends of the finished package, a stream of compressed air may be directed by means of a nozzle 24 across the top of the core. When a sufficient number of turns of thread have been thus wound on the core to start the wind, the retaining fingers 22 are retracted therefrom.

During the next movement of the turret, the traverse guide 12 is moved into operative relation with the turns of thread on the core, and the spindle and guide are rotated so as to cross-wind the thread on the core.

The winding operation continues during the subsequent intermittent movement of the turret until a predetermined yardage of thread has been wound on the core as determined by the diameter 40 of the mass of thread. When the mass of thread is built up to a predetermined diameter or bulk, the winding spindle and traverse guide are brought to rest and remain at rest during the continued rotation of the turret to complete the 45 cycle.

In the case of shuttle bobbins, for example, it is essential that the bobbins shall not exceed a specified diameter. The stopping of the winding when the bobbin has reached a predetermined 50 diameter may result in some variation in yardage of the wound cops owing to variation in sizes of the thread and variation in tension. It will be understood that where it is desired to secure an exact predetermined yardage in the bobbins or 55 cops independently of variation in the sizes of the thread and tension, suitable thread measuring devices (not shown) may be employed which instead of depending on the diameter of the mass, stop the winding when a predetermined yardage 60 has been wound irrespective of variations in sizes of the thread or in the thread tension.

The continued intermittent movement of the turret carries the wound bobbin on its spindle to a station C where the traverse guide, the bobbin 65 and spindle are indexed in a predetermined angular position.

At the next station D devices act to fasten and sever the thread and to temporarily secure the supply end of the thread in the clip 18. When 70 the bobbin reaches station D cooperating thread locators 26 are advanced into position to receive between them the stretch of thread extending from the wound mass to the thread traverse guide (Fig. 44). The locators 26 then move concen- 75

trically to the axis of the winding spindle to deflect the thread upwardly and outwardly into the position shown in full lines in Fig. 45. Devices comprising a tucker locator or feeler 28 and a tucking finger 30 are then advanced, and when the feeler 28 engages the surface of the wound mass, the locators 26 are retracted a distance so as to position the thread in a notch 32 in the end of the tucking finger 30. The feeler and tucking finger are then further advanced substantially tangentially to the surface of the wound mass so as to cause the tucking finger to loop the thread and to force the loop beneath a plurality of stretches of thread of the outer layer adjacent one side of the V of the wind.

In some cases cops are so wound that one or more depressed V-shaped surface portions are formed, as in the case of so-called "one and one-half wind", "two wind", etc., where the winding spindle makes approximately one and one-half, two, or more revolutions to each cycle of operation of the traverse guide. In the case of so-called "single wind" cops where the winding spindle makes one revolution to each cycle of operation of the traverse guide, no depressed V is formed, there being no crossing of the thread except at the edges of the cop. In the case of cops of the first-mentioned wind where one or more depressed V's are formed, it is preferable that the loop be tucked beneath the stretches of thread adjacent one side of one of the V's, first beneath the last laid stretch and then beneath two or more of the next preceding laid stretches. Also, it is preferable that the point of tucking-in of the loop shall be spaced in proximity to the apex of the V so that there will be no danger of the tucking operation sloughing the thread at the edge of the cop and the loop is securely pinched by the tightly held portions of the cross threads adjacent the apex. In the case of cops of a single wind, the tucking-in is preferably effected near the peripheral center of the cop so as to avoid danger of sloughing of the thread during this operation.

In order to cause the tucking finger 30 and feeler 28 to properly operate on the cop during the fastening operation, the traverse guide and winding spindle are indexed after the completion of the winding of each cop so as to position the cop in a predetermined angular position with respect to the formation of the last laid helical coils of the wind.

When the loop of thread is thus positioned beneath the outer lay of the thread, the outer locator 26 moves inwardly to grip the thread against the inner locator and cause the thread to engage the edge of a knife 34, the outer locator 26 cooperating with the edge of the knife to sever the thread. The severed supply end of the thread is then carried by the locators 26 inwardly over the clip 18 and then back so as to cause the end of the thread to engage in the clip, whereupon the locators open to release the thread and are returned to their initial position. Upon severing of the thread the feeler 28 and tucking finger 30 are retracted from the thread mass, leaving the loop tucked under the outer coils.

The tucking finger 30 has an extension or horn 33 which first enters beneath the outer coils to provide a space to receive the loop in the thread. The end of the horn is somewhat wedge-shaped with rounded edges so as to permit it to easily enter beneath the coils without danger of splitting the wound thread.

The next movement of the turret after the fastening and severing of the thread, carries the

winding head with the wound bobbin thereon to a station E where the wound bobbin is removed from its winding spindle. The means for thus removing the bobbin comprises a doffing blade 36 (Figs. 1 and 54) which is secured on the end 5 of a rod or plunger 38. This doffing blade 36 is provided with a clearance notch 40 which is entered by the portion of the spindle back of the wound cop when the winding head is moved into the last-mentioned station. As the turret 10 moves the winding head toward station E, the spindle tip is contracted so as to release the wound cop. When the turret reaches said station the doffing blade is carried by its plunger 38 outwardly so as to engage one side of the 15 thread mass and carry the bobbin therewith so as to discharge it from the spindle.

The doffing blade on its rear side carries a spring member 42 which is arranged closely adjacent the surface of the spindle. In case no 20 thread is wound on the core, the doffing blade 36 passes over the core until the end of the core is engaged by the edge of the member 42, whereupon said member carries the core therewith from the spindle. The wound cop drops 25 from the spindle into a chute 44 which directs it into one of a series of receptacles 46 on a rotating table 48. There are twelve receptacles 46 and the table 48 is intermittently rotated in timed relation to the turret, so that the wound 30 bobbins discharged from each spindle are delivered to a separate receptacle. By this means different colors or sizes of threads may be wound on different spindles and kept separate.

From bobbin doffing position, the next movement of the turret returns the winding head to the core receiving station A, first described, ready to receive another core to be wound. The foregoing is a description of a cycle of operation of the machine for each spindle.

The turret 8 (Figs. 1, 3 and 6) is secured on the upper end of a tubular shaft 50 which extends through and is journaled in a bearing sleeve 52 secured in an aperture in a table 54 that forms a part of the machine frame. The 45 turret is driven through a Geneva gearing comprising the usual star-shaped driven member 56 secured on the lower end of the hollow shaft 50, and a driving member 58 secured on the upper end of a vertical shaft 60. The shaft 60 (Fig. 3) is driven through gears 62 by a shaft 64 which is connected through reducing gears 66 with the shaft of an electric motor 68.

Each of the winding spindles 18 consists of a tubular member (Fig. 15), the core receiving 55 outer end or tip of which is provided with slots 70 so as to enable said end to be expanded to secure the core thereto when the core has been positioned thereon against the shoulder 17 from the magazine tube 16, and to be contracted to 60 release the core preliminary to the discharge of the wound bobbin from the spindle.

The end of the spindle 18 is thus expanded by means of a plunger rod 72, the outer or forward end of which is tapered and extends into the 65 slotted tip of the spindle so that upon forward movement of the rod, said end of the spindle is expanded and upon retraction of the rod the resiliency of the end of the spindle returns it to its initial contracted condition.

The spindle 18 is mounted to turn in a ball-bearing 74 mounted on the outer side of the turret. The spindle is held from axial movement by a shoulder 75 thereon which engages the inner side of said ball-bearing 74 and 75

a collar 76 screw-threaded thereon which engages the outer side of the bearing 74. The spindle 10 is driven through a friction cone 78 on the rear end thereof which is adapted to be moved into driving engagement with a continuously driven friction wheel 80, the friction cones of all of the spindles being driven by said wheel 80. Each friction cone 78 is mounted to slide longitudinally on the inner end of the spindle 10 but rotates the spindle therewith through keys 82 thereon that are received in longitudinal slots in the spindle. The friction cone 78 is mounted on a ball-bearing 84 on the reduced inner end of an internally threaded sleeve or nut 86, which is threaded on a fixed sleeve 88. Upon turning the nut 86 in one direction, the nut is shifted so as to position the friction cone 78 into engagement with the friction wheel 80, and upon turning the nut in the opposite direction the cone 78 is disengaged from the friction wheel 80. The nut 86 is thus turned by means of an arm 90 (Figs. 10 and 17) which is adjustably secured on the periphery of the nut and is urged in a direction to move the cone 78 out of engagement with the friction wheel 80 by means of a spring 92. The end of the arm 90 carries a cam roll 94.

When the thread retaining fingers 22 have gripped the core at station B and the upper finger has gripped the thread on the core, a cam member 96 is advanced into engagement with the cam roll 94 so as to turn the arm 90 a sufficient distance to move the friction cone 78 into light engagement with the friction wheel 80, thus causing the winding spindle to rotate to start the wind. As the winding head is carried by the turret from the last-mentioned station B, the cam roll 94 rides up over the cam member 96 to still further swing the arm 90 upwardly so as to position a roll 98 thereon into position to engage beneath a latching arm 100 which as the cam roll 94 leaves the cam member 96 latches the cone 78 into firm driving engagement with the friction wheel 80. As the friction cone 78 is thus latched in operative engagement with the friction wheel 80, the traverse guide 12 and bridge 13 are moved upwardly into operative engagement with the partially wound core.

The thread traverse guide 12 (Figs. 10, 14, 15 and 16) is secured on a sleeve or hollow shaft 102 which is rotatably mounted on a stud 104 which projects from a pivoted arm or casing 106. The traverse guide 12 is secured on its shaft between a pinion 108 formed on the shaft and a nut 110 screw-threaded on the outer end of the shaft. The casing 106 is in the form of an arm which is pivoted in a sleeve 112 secured in an aperture in the turret, the arm having a hub or boss 114 mounted to turn in the sleeve.

The traverse guide 12 is driven from the spindle through the pinion 108, intermediate gear 115, and a gear 116, which is secured on the end of a shaft 118 that extends through and is journaled in a bushing 120 in the boss 114. The inner end of the shaft 118 carries a gear 122 which engages one side of twin gears 124, the other twin gear being driven by a pinion 126 on the spindle. The twin gears 124 are mounted to turn on a bushing 130 which is secured by a removable pin 132 between the arms of a forked arm 134 which is pivotally mounted on a bushing sleeve 138. The twin gears 124 may be changed to change the lay of the bobbin upon removing the pin 132. In applying a new set of twin gears, the pin 132 is inserted through the proper one

of a series of apertures 140 in the arm 134 and through the bushing 130 of the twin gears. The forked arms 134 may be then swung in position to mesh the twin gears with the gear 126 on the spindle and the gear 122 connected with the thread traverse guide. The forked arm 134 may be held in the position moved by means of a stop screw 142 (Fig. 17) secured to the turret and engaging one side of the arm.

After the start of the winding at the last-mentioned station B, at the beginning of the next movement of the turret, the pivoted casing 106 is moved about its pivot so as to move the thread guide and bridge 13 into operative engagement with the thread on the partially wound core, the thread guide and bridge being in retracted position during the operation of starting the wind. The casing 106 is thus moved by means of a vertically arranged carrier 144 (Fig. 14) which is pivotally connected with the free end of the casing 106 by means of a bushing 146 which is mounted to turn in an aperture in said end of the casing (Fig. 16). The lower end of the carrier 144 carries a cam roll 148 which engages in a cam groove in a member 150, the member 150 being secured on the table concentric with the axis of the turret. The engagement of the cam roll 148 in the cam groove in the member 150 maintains the traverse guide 12 and bridge 13 retracted from the spindle until the cam roll reaches the incline 152 of the groove, whereupon a weight 154 (Fig. 30) connected with the carrier moves the carrier, casing 106 and the thread guide upwardly and maintains the thread guide and bridge in operative engagement 35 with the partially wound core after the cam roll 148 leaves the end of the member 150. The carrier 144 is connected with the weight 154 through a rod 156 which is pivotally connected by a pin 158 with an arm 160 secured on a rock-shaft 162 40 that carries an arm 164 on which the weight is secured by means of a pin 166. The pivot pin 158 may be inserted in any one of a series of holes 159 in the arm 160, and the pin 166 may be inserted in any one of a series of holes 167 in 45 the arm 164. By these adjustments the degree of pressure of the thread guide on the thread mass may be adjusted.

The thread for each winding head is supplied from a package 168 (Fig. 3) supported on a creel 170 carried by the turret, the top of the creel also carrying the weights 154. The thread from the package 168 passes through a suitable thread guide 172 and an upper tension 174 on the carrier 144. This upper tension 174 maintains a slight 50 tension on the thread independently of the winding tension presently described. From the tension 174 the thread passes down between tension disks 176 on the carrier 144. The tension of these disks 176 on the thread is controlled during the winding by the growth of the bobbin. The disks 176 (Fig. 16) are pressed towards each other by a spring 178 interposed between a shoulder on a sliding collar 180 engaging one of the disks, and a nut 182. The collar 180 is mounted to slide 55 on a shaft 184 which extends through and is mounted to turn in the bushing sleeve 146 which provides the pivotal connection between the carrier 144 and the pivoted casing 106. By adjustment of the nut 182 tension of the spring may 60 be varied. The shaft 184 is provided with a spiral groove 186 which receives a pin or lug 188 on the inside of the bushing sleeve 146. Upon turning the shaft in opposite directions the tension of the spring 178 may be varied. The shaft 75

- is thus turned to decrease the tension to a proper degree during the growth of the bobbin, by means of an arm 189 secured on the inner end of the shaft 184 and provided with an elongated slot 5 that receives a pin 190 secured on an arm 192 fastened to the turret. As the carrier 144 is moved downwardly by the bridge due to the growth of the bobbin, the arm 189 turns the shaft 184 in a direction to decrease the tension.
- 10 The arm 192 is fastened by means of a clamping bolt 193 which extends through a slot in the arm and screw thread in an aperture in the turret. This permits the arm 192 to be adjusted longitudinally to vary the tension.
- 15 From the lower thread tension 176, the thread is passed over pins 194 projecting from the pivoted casing 106 and looped beneath a drop wire 196. The drop wire 196 is pivoted at 198 on a projecting arm on the pivoted casing 106. The 20 drop wire is provided with a weight 200.
- When the traverse guide and bridge move up into operative relation with the bobbin, the thread lifts the drop wire therewith. In case the thread fails to start winding upon release 25 of the thread by the retaining fingers 22, the drop wire drops to its lowest position and rests upon a release hook 202 presently described. In this condition, as the turret moves the winding head from the thread starting station B, a pin 30 204 projecting from a blade 206 secured to the drop wire rides up on an inclined surface 208 on the upper end of a support 210 secured to the frame table. The engagement of the pin 204 with the inclined surface 208 causes the drop 35 wire to swing upwardly until the pin 204 rides off of the end of said inclined surface, whereupon the drop wire is free to fall. During the time that the pin 204 is riding up on the inclined surface 208, the vertical carrier 144 is 40 moved upwardly to move the traverse guide and bridge into operative engagement with the bobbin. This upward movement of the carrier 144 also moves the release or knock-off hook 202 upwardly therewith. This hook is formed on 45 the lower end of a rod 212 which is mounted to slide vertically in a guide on the carrier 144. The upper end of the rod 212 is provided with a hook 214 which when the carrier is in its uppermost position is positioned over the end of an 50 arm 216. The arm 216 is secured on one end of a shaft 218 which extends through the bushing 138 on which the fork arm 134 that carries the gainer gears are mounted (Fig. 15). The other end of the shaft 218 carries the latch 100.
- 55 The shaft 218 is urged in a direction to swing the latch downwardly by means of a spring 220. In case the wind has not been started and the drop wire drops down after the pin 204 passes the inclined surface 208, the drop wire strikes 60 the release hook 202, causing the rod 212 to be carried downwardly and through the hook 214 releasing the latch 100 from the roll 98, thus disconnecting the friction cone 78 from the driving wheel 80. The winding spindle is thus disconnected from its driving means and remains in 65 this condition until after another bobbin core is placed on the spindle at the start of the next cycle of operation of the machine.
- In case breakage of the thread occurs at any 70 time during the winding operation, the drop wire drops and thus disconnects the head from its driving means. Also, in case the drop wire drops because of breakage of thread, when the turret reaches a predetermined point in its travel the 75 rotation of the turret is automatically stopped
- and the machine stopped. Such stoppage of the machine is accomplished by the engagement of the blade 206 on the drop wire with a member 222 (Figs. 1 and 32) which through a mercury switch 224 closes the circuit connection 5 hereinafter described. The operating member 222 for the mercury switch is located so as to stop the machine in a position where the winding head that initially has been thrown out of operation is conveniently accessible to the 10 operator. This enables the operator to re-fasten the end of the thread in the clip 18, thus permitting that spindle to start winding in the usual manner at the next cycle. The operator may then again throw the machine into opera- 15 tion, as hereinafter described. A knife 225 (Fig. 23) is arranged adjacent the clip 18 so as to permit the thread to be cut thereby and the proper length end positioned in the clip.
- Thus upon dropping of the drop wire when 20 the winding fails to start, the winding head is thrown out of operation. Also in case the thread should break during the winding operation, the winding head is thrown out of operation. In both cases the automatic units are 25 thrown out of operation and the machine stopped when the turret reaches a predetermined position so as to enable the operator to re-clip the supply end of the thread.
- The device 14 which removes a core 2 from 30 the magazine tube 16 and positions it on the end of each spindle when the spindle is at station A (Figs. 1, 10, 11 and 15), comprises a gate which by means of a stud 226 is pivoted on a head 228 of a carrier 230 which is mounted to 35 slide in a guideway in a support 232, the carrier being held from turning by a key 234 which extends into a slot in the support. The carrier 230 is urged outwardly to hold its head 228 against the end of its support 232 by means of 40 a spring 236.
- The gate 14 is provided with a recess 238 in which is mounted a plunger 240 which is pressed by means of a spring 242 toward the open end 45 of the recess, this movement of the plunger being limited by nuts 244 secured on the outer end of the stem of the plunger. The gate 14 is normally in a position so as to position the recess 238 in registry with the lower end of the magazine tube 16 so as to permit a bobbin core from 50 the tube to drop down into the recess and against the end of the plunger 240. When a winding head has been carried to a position opposite the gate 14, the gate is swung forwardly so as to position the core carried thereby into 55 alinement with the end of the winding spindle 10. The gate is then moved so as to position the core on the tip of the spindle (Fig. 11). The tip of the spindle is then expanded to securely hold the core in position, and then the gate is 60 retracted from the spindle, allowing the core to remain on the spindle. From this position the gate is swung upwardly to re-position its recess in alinement with the end of the magazine tube 16 to receive the next core. During the movement of the gate into and out of core receiving position, the column of cores in the magazine tube is held by the engagement of the lower end of the lowermost core with the surface 246 of the gate. The spring pressed plunger 240 on 70 75 which the core rests when in the recess 238, ensures the core being positioned against the shoulder 17 on the tip of the spindle.
- The gate 14 is operated, as described, through a rod 248 which carries a cam roll 250 (Figs. 3

and 5) that is received in a cam groove 252 in a cam disk carried by a shaft 254 which is driven through gears 256, shaft 258, gears 260, and shaft 262 which is driven from the Geneva drive 5 shaft 60 through beveled gears 264.

The magazine tube 16 leads from a hopper 266 supported above the machine. This hopper is provided with an agitating member 268 which is reciprocated vertically to agitate the bobbin cores 10 in the hopper and cause them to enter the upper end of the magazine tube. This agitating member is thus reciprocated through a link 270, and arm 272 which is secured to a rock-shaft 274 (Figs. 3 and 12). The rock shaft 274 is operated 15 through an arm 276 that is connected through a link 278 with a crank disk 280 on the shaft 254.

In order to overcome the danger of the bobbin cores becoming stuck in the magazine tube, we provide a lifting pawl 282 (Figs. 10 and 11). This 20 pawl 282 is pivotally mounted on a bracket 284 secured to the link 270. The lower end of the pawl is provided with a hook 286 which is adapted to extend through a slot 286 in the magazine tube. As the lifting pawl 282 is moved downwardly during the down stroke of the link 270 the hook rides over the sides of the cores. Upon the upstroke of the link 270, the hook 286 engages beneath the lower end of one of the cores and lifts the column of cores above it upwardly until 25 the inclined end of a screw 290 on the lifting pawl 282 engages the upper end wall of the slot whereupon the hook is pulled out from beneath the column of cores, allowing the cores to drop down at the moment that the gate reaches a position to 30 receive a core. The pawl 282 is turned to press the lower end thereof against the side of the magazine tube by means of a spring 292.

The gripping jaws 20 for removing the end of the thread from the clip 18 and laying the thread over the bobbin core when the winding head reaches station B as above described, are mounted to slide in a block 294 which is pivoted by means of a stud 296 to an arm 298 on a carrier 300 (Figs. 1, 14, 18 and 26 to 28). This carrier 300 consists of a sleeve which is mounted to slide longitudinally in a bearing 302 on the machine frame, the sleeve being held from turning in the bearing by means of a pin 304 secured to said arm and extending through an aperture in the machine frame. A rock-shaft 306 is journaled in this carrier sleeve 300 and carries at its inner end a crank arm 308 which is pivotally connected by means of a pivot block 310 with the inner jaw 20, this jaw having a hooked-shaped lower end 312. A spring 314 is coiled about the upper portion of the inner jaw 20 and interposed between the block 310 and a block 316 which is secured on the upper end of the outer jaw 20.

When a winding head has reached thread starting position at station B, the carrier 300 is moved 60 carrying the shafts 306 and the gripping jaws 20 forwardly to position the lower ends of the jaws opposite the stretch of thread extending from the clip 18 to the traverse guide 12. The crank arm 65 308 then moves the inner jaw downwardly causing the inclined surface on the lower end of the jaw to ride over the thread so as to position its gripping surface adjacent the under side of the thread. During the downward movement of the inner jaw, the outer jaw is carried therewith through the spring 314 until the block 316 strikes the upper end of the pivoted block 294, whereupon the movement of the outer jaw is arrested so that when the inner jaw reaches its lowermost position the gripping surfaces of the jaws are sepa- 70 75

rated so as to receive the thread between them. The crank 308 is then turned in the opposite direction which first moves the inner jaw upwardly until its gripping surface causes the thread to be gripped between it and the lower end of the outer 5 jaw, whereupon the two jaws are moved upwardly together carrying the thread therewith, thus removing the thread from the clip 18.

When the thread is thus gripped by the gripping jaws 20, the carrier 300 moves the jaws outwardly so as to position the gripped end of the thread in the center of the bobbin core and at the same time the jaws are moved upwardly so as to carry the end of the thread above the core. As the crank arm 308 passes its dead center, the 15 jaws are swung about the pivot pin 296 of the block 294, thus carrying the thread over the core (Fig. 28).

The retaining fingers 22 are pivotally mounted on pins 318 (Figs. 24 and 25) in slots 320 in the inner end of a bushing 322. The retaining fingers are held in open position by means of springs 324 which are received in recesses in a sleeve 326 which embraces the forward slotted end of the bushing 322. The bushing 322 is mounted for 25 rotary movement in a ball-bearing 328 which is mounted in an enlarged head on a tubular casing 330. The retaining fingers 22 are adapted to be moved toward each other so as to grip the core and to cause the upper finger to engage the 30 thread by means of a conical head 332 which is mounted for rotary movement on the reduced end of a plunger 334. The conical head 332 is free to rotate on a ball 336, and is held from axial movement by a pin 338 which is received in an 35 annular groove in the reduced end of the plunger 334.

The retaining fingers 22 are moved forwardly into position to engage the core by means herein-after described, connected with the tubular casing 330. Previously to the forward movement of the retaining fingers 22, the fingers are indexed so as to insure that the longer finger will be positioned centrally over the top of the core. This indexing of the fingers is effected by means of a 45 latch lever 340 (Fig. 19) which is pivoted at 342 on the head of the casing 330. The forward end of the latch lever 340 engages in a notch 344 (Fig. 21) in the sleeve 326, the end of the latch lever being pressed toward the surface of the 50 sleeve by means of a spring 346.

As the retaining fingers are moved forwardly to engage the core, an extension on the lever 340 rides up over an inclined surface 348 which swings the latch lever to disengage its end from 55 the notch in the sleeve 326 (Fig. 19).

When the retaining fingers have thus gripped the core and the thread is held by the upper finger and the spindle is rotated to start the wind, the grip of the retaining fingers on the core and 60 spindle causes the fingers and their carrier to rotate with the spindle on the ball-bearing 328.

Preliminary to retraction of the fingers from the core, after a predetermined number of turns are wound on the core to start the wind, the conical 65 plunger head 332 is retracted so as to relieve the grip of the fingers on the core.

When the fingers have been retracted from the core and returned to their inoperative position, a friction segment 350 (Fig. 21) engages the outer 70 periphery of a friction collar 352 on the sleeve 326 to rotate the sleeve until the end of the latch lever 340 snaps into the notch 344, thus re-indexing the fingers.

The friction disk 350 carries a cam lug 354 75

which upon engagement of the retaining fingers 22 with the core on the spindle, strikes one end of a bell-crank 356 so as to turn the bell-crank (Fig. 28). The other arm of the bell-crank is positioned beneath the block 316 of the outer gripping jaw, so that upon engagement of the cam lug 354 with the bell-crank this jaw is retracted to release the thread.

The carrier 300 for the gripping jaws 20 is shifted as above described through a cam lever 358 (Figs. 18 and 21) which is pivoted at 360 and carries a cam roll 362 which engages a groove in a cam 364 on a shaft 366. This shaft 366 is driven through gears 368, shaft 370 (Fig. 8), gears 372, and shaft 374 which is driven through gears 376 by the Geneva drive shaft 60.

The rock-shaft 366 for opening and closing the jaws 20 is actuated as above described, through a pinion 378 formed on the end of the shaft which 20 is engaged by a gear segment 380 pivoted on a pin 382 on machine frame. This gear segment 380 is actuated through a forked cam lever 384 which carries a cam roll 386 engaging a groove in the face of a cam 388 carried by the shaft 366.

25 The tubular casing 330 that carries the retaining fingers 22 is shifted, as above described, through a sliding cam block 390 (Figs. 18 and 20) which engages in a grooved collar 392 on the tubular casing and carries a cam roll which 30 engages in a groove in a cam 394.

The plunger rod 334 for actuating the fingers 22 is actuated by a sliding cam block 396 which engages a grooved collar 398 secured on the rod. The cam block 396 carries a cam roll which 35 engages a cam groove in a cam 400. The cam blocks 390 and 396 are mounted to slide on rods 397.

The friction segment 350 is secured on a shaft 402 which is driven through a gear 404 secured 40 on one end thereof, which is operatively engaged by a gear 406 secured on the cam shaft 366 (Fig. 18), the segment 350 being continuously driven.

The means for stopping the winding of each bobbin when a predetermined diameter has been 45 wound, comprises a cam or knock-off disk 410 which is mounted on each carrier 144 (Fig. 14). The downward movement of the traverse guide 12 and the bridge 13 caused by the building up of the thread mass, moves the associated carrier 144 downwardly, and when the thread mass 50 reaches a predetermined diameter and hence is of a predetermined yardage, the knock-off disk 410 strikes the arm 216 to release the latch 100 from the roll 98 (Fig. 17). This allows the arm 99 to be moved by its spring 92 to shift the friction cone 78 connected with the winding spindle out of engagement with the driving wheel 80, thus bringing the spindle and traverse guide to rest.

Each knock-off disk 410 is secured on a pin 412 60 which is mounted to turn in an aperture in the carrier 144. On the pin 412 there is a knob 414 which is provided with ratchet teeth 416 adapted to be engaged by a spring-pressed detent 418. It will be apparent that by adjusting the angular 65 position of the knob 414 the knock-off disk 410 may be adjusted angularly to vary the movement required of the carrier 144 in order to throw out the driving means for the spindle and thus the bulk or diameter of the package may be varied as desired. It will be understood that the yardage 70 for any given diameter of thread winding, may be varied by varying the thread tension and also the pressure of the bridge on the thread mass.

After the completion of the winding of a bobbin, 75 the carrier 144 and thread guide 12 remain in the

position which they assume when the drive for the winding spindle is thrown out, until the cam roll 148 on the lower end of the carrier 144 again enters the cam groove 152 (Fig. 34), whereupon the carrier together with the pivoted casing 106 5 which carries the traverse guide 12 and bridge 13 is moved downwardly to a predetermined position, this occurring at the end of the movement of the turret to station "C". Such positioning of these parts alines the outer end face of the 10 traverse guide with a friction disk 420 (Fig. 35) which is secured on the end of a head 422 carried by a shaft 424. The shaft 424 rotates continuously and upon the traverse guide reaching said predetermined position, the shaft 424 is shifted 15 longitudinally to cause the friction disk 420 to engage the outer end face of the traverse guide 12 to rotate the guide and the associated spindle in a direction to unwind the bobbin. During this reverse movement of the traverse guide and 20 spindle, the slack of the thread is taken up by the drop wire 196 so as to keep the thread taut. When the friction disk 420 has rotated slightly more than one revolution in engagement with the end of the traverse guide, the shaft 424 is shifted 25 to retract the friction disk from the traverse guide.

During this reverse rotation of the traverse guide and spindle, the traverse guide and spindle are indexed to position the wound cop in a 30 predetermined angular position with respect to the formation of the last laid helical coils as above described. To provide for this, an index disk 426 is secured on the inner end of the shaft 118 (Figs. 16 and 17). The index disk 426 is 35 provided with a notch 428 which, during said reverse rotation of the traverse guide and spindle, when these parts reach a predetermined angular position is entered by the end of an index latch 430, thus locking the disk and hence the traverse 40 guide and spindle in said predetermined angular position. The latch 430 is pivoted at 432 on the underside of the turret. The latch is provided with a downwardly spring-pressed detent 434 in the form of a ball which, as the winding head approaches said last-mentioned station C engages the top surface of a segmental track 436 which is concentric with the axis of the turret (Figs. 6 and 17). The engagement of the detent ball 434 with this track causes the end of the latch 430 to 50 be pressed against the surface of the index disk 426 so that when the notch 428 comes opposite the end of the latch, the latch will snap up into the notch. The index disk 426 continues to hold the traverse guide and winding spindle in said 55 predetermined angular position until the winding head receives the next core and reaches the thread starting station B, whereupon the detent ball 434 rides off the segmental track 436 to release the index disk.

The shaft 424 that carries the friction disk 420 is continuously rotated by a belt 438 (Figs. 1, 9 and 35) which passes over a pulley on said shaft and the upper side of a double pulley 440 which is driven by a belt 442 that passes over the lower 65 side of the double pulley and over a pulley 444 on a vertical shaft 446, hereinafter referred to.

The shaft 424 is shifted axially to move the friction disk 420 into and out of engagement with the face of the traverse guide, as above described, 70 by means of a lever 448, one end of which engages a grooved collar 450 secured on the outer end of the shaft 424, and the other end of which is connected by a link 452 with one arm of a bell-crank 454. The other arm of this bell-crank car- 75

ries a cam roll that engages a cam 456 secured on the shaft 446. The cam roll of the bell-crank 454 is held in contact with the surface of the cam by means of a spring 458 connected with the lever 448.

Regardless of whether or not a bobbin has been wound on the spindle the traverse cam and spindle are indexed, as above described, so as to place the traverse cam and spindle in position to enable the automatic units to properly function.

During the movement of the winding head from the station C where the traverse cam and spindle are indexed, to the station D where the thread is fastened, the cam roll 448 by engagement in the cam groove 152 moves the carrier 144 and parts connected therewith downwardly to their lowermost position (Fig. 34). Said parts remain in the positions thus moved until after the start of the winding.

The tucking finger 38 and the tucker locator or feeler 28 are carried by a spindle 460 (Figs. 1, 37, 38, 41 and 44). The tucking finger 38 is detachably secured on the end of the spindle 460 by a chuck 462. The feeler 28 is secured to the spindle by means of a clamping collar 464, the collar 464 being adjustable both axially and circumferentially of the spindle 460 to adjust the position of the feeler. The spindle 460 is secured in an eccentric sleeve 466 mounted in a block 468. The spindle 460 has its outer end screw-threaded at 470 in the sleeve 466 so as to enable the spindle to be axially adjusted, the spindle being held in adjusted position by a lock nut 472. The eccentric sleeve 466 is adapted to be turned to vary the lateral position of the tucking finger 38 and feeler 28 and clamped in adjusting position by means of a flange 474 at the outer end thereof engaging one end of the block 468, and a nut 476 screw-threaded on its inner end and engaging the inner end of the block 468. The block 468 is pivoted on a stud or screw 478 which is secured on a slide 480 that is mounted to slide at the proper angle in guideways in a support 482 on the machine frame. The pivoted block is held in a predetermined position by means of a spring 479 (Fig. 38) which yieldingly maintains a lug 481 on the block in contact with the end of a stop screw 483 on the slide 480.

The tucker locator or feeler 28 is set so that it will, after engagement with the bobbin, ride up on the bobbin, the pivoting of the carrier block 468 allowing for such movement of the locator against the tension of the spring 479. The purpose of this is to properly locate the tucking finger regardless of the diameter of the bobbin.

The slide 480 is actuated to move the tucking finger 38 and feeler 28 toward and from the bobbin through a turnbuckle 484 which connects the outer end of the slide with one end of a cam lever 486. The lever 486 is pivoted at 488 and its other arm carries a cam roll 490 which engages in a groove in a cam 492 carried by a cam shaft 494. The shaft 494 is driven through beveled gears 496, shaft 446 (Fig. 8), which in turn is driven through beveled gears 498, shaft 500, and a beveled gear 502 on the end of the shaft which engages the beveled gear 376 on the Geneva drive shaft 60.

The thread locators 26 are carried by an arm 504 which is secured on the end of a block 506 secured on the end of a shaft 508. The arm 504 is mounted on guideways on the block so as to permit the arm to be adjusted radially of the axis of the shaft 508 and the arm is held in adjusted position by means of a cap screw 510

which extends through a slot in the arm and is screw-threaded into the block.

The shaft 508 is in axial alignment with the winding spindle when the spindle is at station D and is rotated to move the locators 26 about the bobbin, as above described (Figs. 44 to 52) by means of a pinion 512 (Fig. 39) formed on the outer end thereof which is engaged by a segmental gear 514 formed on one end of a lever 516 which is actuated through a cam lever 518 that carries a cam roll 520 engaging a cam groove in a cam 522 on the shaft 494.

The locators 26 are moved from retracted position to a position opposite the thread, by means of a cam 519 (Fig. 37), in the groove of which is a cam roll 521 on a block 523 secured to the shaft 508 and mounted to slide on a guide rod 510. The block 523 is adjustably secured to the shaft 508 so as to enable the shaft to be longitudinally adjustable through the block and thus adapt the position of the locators 26.

The outer locator 26 (Fig. 42) is formed on the end of a rod 524, and the inner locator 26 is formed on the end of a tube 526, the rod 524 extending through the tube 526. The tube 526 extends through a sleeve 528 and the inner locator 26 is pressed towards the outer locator by means of a spring 530 coiled about the tube 526 and interposed between the head of the inner locator and the end of the sleeve 528. The knife 34 is secured on the sleeve 528 and its knife edge is normally arranged slightly back of the outer end face of the inner locator. A tubular casing 532 surrounds the sleeve 528 and the knife 34, the tubular casing being secured to the sleeve 528. The end of this tubular casing 532 carries thread guiding horns 534 which serve to guide the thread between the locators as the locators are moved into position to receive the thread between them.

In order to grip and sever the thread, as above described, the outer locator 26 is moved inwardly to grip the thread against the inner locator, and then to move the inner locator therewith against the tension of the spring 530 to carry the gripped thread against the edge of the knife 34, thus severing the thread. To thus move the outer locator, a grooved collar 536 is secured on the outer end of the rod 524 and is engaged by the forked end of a lever 538 pivoted at 540 on the block 504 and pressed in a direction to separate the locators by means of a spring 542. The lower end of the lever 538 when the locators are moved into position to sever the thread, is positioned opposite a plunger rod 544 (Fig. 37) which at the proper time advances and swings the lever 538 to effect the gripping and severing action of the locators. The plunger 544 carries a block 546 which is mounted to slide on the guide rod 510 and carries a cam roll 548 which is received in a groove in a cam 550 carried by the cam shaft 494.

While the winding head is moving from station D where the thread is fastened and severed, to station E where the completed bobbin is doffed from the spindle, the expander rod 72 for the spindle tip (Fig. 10) is retracted to release the bobbin. The expander rod 72 is thus retracted against the tension of a spring 552, coiled about the rod, by means of an arm 554 (Fig. 15), one end of which is pivotally connected with the outer end of the expander rod and its other end secured on one end of a vertical shaft 556. The lower end of the shaft 556 has an arm secured thereon which carries a cam roll 558. As the winding head leaves the thread fastening and severing station D, the cam roll 558 engages a cam surface 560 on

2. segmental block 562 (Fig. 6). As the turret continues to rotate the cam roll by engagement with said cam surface retracts the spindle expander rod 72.

5 The spindle tip remains contracted until another core has been placed thereon at the core receiving station A, whereupon a section 563 of the cam segment 562 is turned about a pivot 564 in a direction away from the cam roll, allowing the expanding rod to advance to expand the tip 10 of the spindle by the action of its spring. The cam section 563 is thus moved by an arm 566 to which said section is secured. The arm 566 is thus turned by a spring 568 connected to the arm. The cam block section 563 is restored to 15 position to be engaged by the cam roll 558 through a link 570, arm 572, shaft 514, arm 576, link 578, arm 580 and arm 582 which carries a cam roll that engages a cam 84 carried by the shaft 500.

20 The mechanism for moving the doffing blade 36 into operative position, as a winding head approaches station E so that when the winding head reaches said station the completed bobbin is positioned adjacent the outer side of the doffing blade, and for moving the blade to doff the bobbin 25 from the spindle comprises an arm 586 (Figs. 1 and 54) having one end connected with the carrier rod 38 through a pin and slot connection and its other end pivoted at 588. The arm 586 is actuated through a link 590 and cam lever 592 30 which carries a cam roll that is received in the groove of a cam 594 secured on the shaft 494 (Fig. 37).

35 After the doffing of the bobbin, the winding head is moved to the station A to receive the next core, thus completing a cycle of operation of the machine.

40 The reciprocating thread starting cam 96 (Fig. 17) is mounted on a carrier slide 596 which is mounted to slide in guideways on the top of the frame table. The cam is shifted as above described through a link 598, arm 600, arm 602, link 604, arm 606, and arm 608 that carries a cam roll which engages a cam 610 mounted on the shaft 374 (Figs. 6 and 8).

45 The continuously driven friction wheel 80 (Fig. 3) for driving the winding spindles, is mounted on the upper end of a vertical shaft 612 which is mounted on ball-bearings 614 and extends through the hollow shaft 50 that carries the turret. The lower end of the shaft is connected 50 through gears 616 with the shaft of an electric motor 618.

55 The friction wheel 80 is adapted to be adjusted vertically to vary its frictional driving contact with the friction cones 78 of the winding spindles. To provide for this, a collar 620 is secured by pins 622 (Figs. 3 and 4) to the upper end of the hub of the friction wheel. This collar carries outwardly spring-pressed pins 624 which 60 are adapted to engage ratchet teeth 626 on the inside of a cap 628. A screw 630 is screw-threaded into a recess in the upper end of the shaft 612 and has a stem which extends through the collar 620 and the cap 628. The screw stem is secured 65 to the cap. With this construction, upon turning the cap 628 the screw may be adjusted to raise or lower the friction wheel, the screw being held in adjusted position by engagement of the pins 624 with the ratchet teeth 626.

70 The receptacle carrying table 48 for receiving the bobbins as they are discharged from the machine is mounted for rotation on a fixed shaft 632 (Figs. 2, 4, 6 and 7). The table 48 is intermittently rotated in unison with the turret 75 through a ratchet wheel 634 which is secured on

the under side of the table and is engaged by a spring-pressed pawl 636 carried by an arm 638 that is connected through a rod 640 and cam roll 642 with a cam 644 carried by the shaft 262, the cam roll being held against the surface of the cam by a spring 646 connected with the cam rod 640.

5 The circuit connection with the starting motor 68 (Fig. 4) is controlled through a snap switch contained in a box 648 (Figs. 9, 57 to 69). This 10 snap switch is controlled by a switch lever 650, which when in the position shown in full lines in Fig. 58, maintains the circuit closed and upon swinging the lever to the position shown in dotted lines, the switch is opened. The switch may be 15 closed through a link 654, stud 656 and a hand lever 658. Upon turning the hand lever 658 in one direction against the tension of the spring 662 connected therewith, the switch lever 650 is turned to close the circuit. Upon this movement 20 of the hand lever 658, a cam surface 664 thereon by engagement with a detent ball 666 raises a lever 668 into latching engagement with a latch 670 that is pivoted at 672 and has its upper end pivotally connected with the core 674 of a solenoid 676. The solenoid 676 is in circuit connection with the mercury switch 224 (Fig. 32). Upon closing the mercury switch 224 by engagement of a lug 206 of a drop wire 196 with the switch member 222, the solenoid 676 is energized thus releasing the latch 670 from the arm 668. The arm 668 is secured on a shaft 678 on which is also secured an arm 680 which engages a grooved collar 682 formed on a sleeve 684 that is mounted to slide on the shaft 500. The sleeve 684 is mounted to 30 turn with the shaft through keys 686 that are received in slots 688 in a collar 690 secured to the shaft. A spring 692 is coiled about the sleeve 684 and interposed between the collar portion 682 and the collar 690. The sleeve 684 carries 40 a crank arm 694 which carries a roll 696.

Upon release of the arm 668, the spring 692 shifts the sleeve 684 so as to place the roll 696 in such position that during its continued rotation it will strike the end of the switch lever 650 45 and move the lever to open the switch, thus stopping the rotation of the turret in a predetermined angular position. The switch may be closed by means of the lever 658 to restart the machine.

50 While the machine is illustrated and described as producing thread cops provided with tubular cores, it is to be understood that the winding may take place directly on the spindle so as to produce coreless cops.

55 As will be evident to those skilled in the art, my invention permits various modifications without departing from the spirit thereof or the scope of the appended claims.

What we claim is:

60 1. In a winding machine, the combination of a turret, a plurality of winding heads carried by the turret each including a winding spindle horizontally arranged, means for intermittently rotating the turret to successively move the winding heads to a predetermined station, a magazine for cop cores in which the cores are arranged one upon the other in end to end relation, a pivoted gate having a recess therein for receiving the lowermost one of the cop cores, said magazine and gate being mounted at said station in fixed position with relation to said turret, and means for turning the gate to position the core in alignment with the spindle when the spindle is at said station, and for relatively moving the gate and spindle to position the cop core on the spindle. 75

2. A structure according to claim 1 in which the cop core when in said recess in the gate is supported by means of a spring-pressed plunger whereby when the gate is moved to position the core on the spindle the plunger will yield in case the application of the core on the spindle is obstructed.

3. In a winding machine, the combination of a turret, a plurality of winding heads carried by the turret each including a winding spindle, means for intermittently rotating the turret to successively move the winding heads to a predetermined station, a cop core being positioned on the winding spindle previously to the winding head reaching said station, means located at said station acting automatically when each winding head is at said station for applying the end of a thread to the cop core and securing it to the core whereby upon rotation of the winding spindle the thread is wound on the core, and means for retracting said applying and securing means from the thread after a predetermined number of coils of thread have been wound.

4. In a winding machine, the combination of a winding head having a winding spindle adapted to receive a cop core thereon and detachably secured thereto, means for applying the end portion of a thread to the core, a rotatable device mounted independently of the spindle for gripping the thread on the core, means for rotating the winding spindle when the thread is thus applied and gripped to the core, said device being rotated with the spindle when gripping the thread on the core, and means for retracting said device after a number of turns of thread have been wound on the core.

5. In a winding machine, the combination of a winding head having a winding spindle, said winding spindle being adapted to receive a cop core thereon with the core secured to the spindle, means for applying the end portion of a thread to the core, retaining fingers for engaging the core between them, one of said fingers retaining the thread upon the core, a rotatable carrier for the retaining fingers arranged in axial alignment with the spindle whereby when the spindle is rotated the carrier is rotated therewith through the engagement of the fingers with the core, and means for advancing said retaining fingers into effective engagement with the core and after a predetermined number of turns of thread have been wound on the core retracting said fingers therefrom.

6. In a winding machine, the combination of a winding head including a winding spindle, a device mounted on the head for detachably holding the free end of the thread, gripping jaws for removing the free end of the thread from said device and applying it to the spindle, devices for securing the thread to the spindle whereby when the spindle is rotated the thread is wound on the spindle, means for retracting said devices from the spindle and thread after a number of turns of thread have been wound on the spindle, and means for rotating the spindle to wind the thread after the thread is secured thereon.

7. In a winding machine, the combination of a turret, a plurality of winding heads carried by the turret each including a winding spindle, means for intermittently rotating the turret to successively move the winding heads to a predetermined station, means for positioning a cop core on the spindle previously to the winding head reaching said station, means acting automatically when the winding head is at said station

for applying the free end of a thread carried by the head to the core, a device located at said station for retaining said end of the thread on the core, means for then rotating the spindle to cause the thread to be wound on the core, and means for retracting said retaining device from the thread and core after a predetermined number of turns of thread have been wound on the core.

8. In a winding machine, the combination of a turret, a plurality of winding heads carried by the turret each including a winding spindle, means for intermittently rotating the turret to successively move the winding heads to a predetermined station, means for positioning a cop core on the spindle previously to the winding head reaching said station, means located at said station acting automatically when each winding head is at said station for securing the free end of a thread carried by the winding head to the core, means for then rotating the spindle to cause the thread to be wound on the core, and means for retracting said securing means from the thread after a predetermined number of coils of thread have been wound.

9. In a winding machine, the combination of a winding head having a winding spindle, a device carried by the head for detachably holding the free end of the thread, devices for removing the thread end from said holding device and for securing it to the thread winding surface of said spindle means for rotating the spindle to cause the thread to be wound thereon, and means for retracting said removing and securing devices from the thread after a predetermined number of coils of thread have been wound.

10. In a winding machine, the combination of a turret, a plurality of winding heads carried by the turret each including a winding spindle, means for intermittently rotating the turret to successively move the winding heads to a predetermined station, and means located at said station acting automatically when a winding head is at said station for securing the free end of the thread carried by the head to the portion of the spindle on which the thread is to be wound, means for rotating the spindle to cause the thread to be wound thereon, and means for retracting said securing means from the thread after a predetermined number of coils have been wound.

11. In a winding machine, the combination of a winding spindle, means for applying the free end of a thread to the spindle, means for rotating said spindle to cause the thread to be wound thereon, means acting automatically when a cop has been wound on the spindle to throw the spindle out of operation, means for severing the thread and for fastening the outer end of the wound thread to the wound thread mass, while the cop is on the spindle, and means for doffing the completed cop from the spindle.

12. In a winding machine, the combination of a turret, a plurality of winding heads carried by the turret, each including a winding spindle, means for intermittently rotating the turret to successively move each winding head to a predetermined station, means for securing the thread carried by each head to the spindle while the head is at said predetermined station, means for rotating the spindle to cause the thread to be wound thereon during the subsequent rotation of the turret, means acting automatically when a thread cop has been wound on the spindle for throwing the spindle out of operation, means acting automatically thereafter and before the

spindle again reaches said predetermined station to index the spindle to position a definite point in the formation of the outer layer of the wind in a predetermined position, and a device cooperating with said indexing means for positioning the stretch of thread extending from the cop in a predetermined position with relation to the peripheral surface of the cop.

13. In a winding machine, the combination of a turret, a plurality of winding heads carried by the turret, each including a winding spindle, means for intermittently rotating the turret to successively move each winding head to predetermined stations, means for securing the thread carried by each head to the spindle when the head reaches one of said predetermined stations, means for rotating the spindle to cause the thread to be wound thereon during the subsequent rotation of the turret after the head leaves said station, means acting automatically when a cop has been wound on the spindle for throwing the spindle out of operation, means acting automatically when the spindle is at another predetermined station to index the spindle so as to position a definite point in the formation of the outer layer of the wind in a predetermined position, and a device cooperating with said indexing means for positioning the stretch of thread extending from the cop in a predetermined position with relation to the peripheral surface of the cop.

14. In a winding machine, the combination of a turret, a plurality of winding heads carried by the turret, each including a winding spindle, means for intermittently rotating the turret to successively move the winding heads to a predetermined station, means for rotating each spindle to cause thread applied thereto to be wound thereon, means acting automatically to stop the rotation of each winding spindle when a thread cop has been wound thereon, means acting automatically when each winding spindle reaches said predetermined station to index the winding spindle to position a definite point in the formation of the outer layer of the wind in a predetermined position and to retain it in said position until after the wound cop has been removed therefrom and thread is applied thereto previously to starting the next wind on the spindle, and a device cooperating with said indexing means for positioning the stretch of thread extending from the cop in a predetermined position with relation to the peripheral surface of the cop.

15. In a winding machine, the combination of a turret, a plurality of winding heads carried by the turret each including a winding spindle, means for intermittently rotating the turret to successively move the winding heads to a predetermined station, means for applying the end of a thread carried by the winding head to the spindle when the spindle is at said station, retaining fingers, a rotatable carrier for the retaining fingers arranged in axial alinement with the spindle when the spindle is at said station, said carrier and retaining fingers being located at said station, means for indexing said carrier and for holding it in indexed position to hold said fingers in a predetermined angular position, means for advancing the carrier to position said fingers at opposite sides of the spindle and then to close the fingers on the spindle with one of the fingers gripping the thread between it and the spindle, means for releasing said indexing means previously to the engagement of said fingers with the spindle and thread whereby upon rotation of the spindle said retaining fingers are rotated

therewith for a predetermined number of windings of the thread on the spindle, and means for retracting the fingers from the spindle and thread when said predetermined number of turns have been wound on the spindle.

16. In a winding machine, the combination of a turret, a plurality of winding heads carried by the turret, each including a winding spindle, means for intermittently rotating the turret to successively move the winding heads to a predetermined station, means located at said station for securing the end of a thread carried by the head to the winding spindle when the head is at said station whereby upon rotation of the spindle the thread is wound on the spindle, controllable means for driving the spindle, means acting automatically when the thread is secured to the spindle to control said driving means to temporarily rotate the spindle to cause a number of turns of thread to be wound on the spindle, and means acting automatically after the winding head leaves said station to control said driving means to rotate the spindle and to maintain the rotation thereof until a thread cop has been wound on the spindle, and means for throwing out said driving means upon the completion of the winding of said thread cop.

17. In a winding machine, the combination of a turret, a plurality of winding heads carried by the turret including a winding spindle, means for intermittently rotating the turret to successively move the winding heads to a predetermined station, means cooperating with each spindle to cross wind a cop on the spindle previously to its reaching said station, means for indexing the spindle to position a definite point in the formation of the outer layer of the wind in a predetermined position while at said station, and a device cooperating with said indexing means for positioning the stretch of thread extending from the cop in a predetermined position with relation to the peripheral surface of the cop.

18. In a winding machine, the combination of a turret, a plurality of winding heads carried by the turret, each including a winding spindle, a friction member, connections between the friction disk and winding spindle to cause the winding spindle and disk to rotate simultaneously, a cooperating friction member, means for rotating the last mentioned friction member, means for moving said friction member into driving engagement with the first mentioned friction member and for retracting it therefrom, a device acting when the driven friction member has been turned to a predetermined position to lock said member in said position, and means acting automatically at a predetermined point in the travel of the turret after the winding head leaves said station for releasing said device.

19. In a winding machine, the combination of a turret, a plurality of winding heads carried by the turret each including a winding spindle, means for intermittently rotating the turret to successively move the winding heads to a predetermined station, means cooperating with each spindle for cross winding a cop on the spindle previously to the spindle reaching said station, means for positioning the cop to position a definite point in the formation of the outer layer of the wind in a predetermined position as they approach said station and for maintaining it in said position while at said station, a device cooperating with said cop-positioning means for positioning the stretch of thread extending from the cop in a predetermined position with relation to the peripheral surface of the cop.

- to the peripheral surface of the cop, and means acting automatically when the spindle is at said station to sever said stretch of thread and secure the end of the thread at a predetermined point 5 on the wound cop.
20. In a winding machine, the combination of a winding spindle, means cooperating with the winding spindle for cross-winding thread thereon to form a cop, the winding having a depressed V 10 in its outer surface and a device for forming a loop in the thread and for tucking the loop beneath a plurality of windings adjacent a side of said V, the tucking of the loop being effected in a direction outwardly from the V.
21. In a winding machine, the combination of a winding spindle, means cooperating with the winding spindle for cross-winding thread on the spindle to form a thread cop, a locating device for positioning a portion of the stretch of thread 15 extending from the thread cop in a predetermined position with relation to the periphery of the cop and a V of the cop, and a tucking finger for engaging the stretch of thread extending from the cop to said locating device and tucking 20 a portion of it beneath a plurality of windings adjacent one side of said V to fasten the thread, a thread severing knife, and means for moving the locator to move the thread into engagement 25 with the knife to sever the thread.
22. In a winding machine, the combination of a winding spindle, a thread traverse guide associated with the spindle, means for actuating the spindle and the traverse guide to cross-wind a thread on the spindle to form a cop, a locating 30 device for moving the stretch of thread extending from the thread cop to the thread traverse guide so as to locate the portion of the thread extending from the thread cop to the locating device in a predetermined position with relation 35 to the periphery of the thread cop, means for then securing the outer end of the thread to the thread cop at a definite point in the cross-winding of the cop, and means cooperating with said thread locating device to sever the thread.
23. In a winding machine, the combination of 40 a turret, a plurality of winding heads carried by the turret, each winding head including a spindle, means for intermittently rotating the turret to successively move each winding head to a plurality of stations, means for applying a cop tube 45 to each spindle when the spindle reaches one of said stations, means for applying thread to the cop tube and throwing the winding spindle into operation temporarily to start the wind when the spindle is at another one of said stations, 50 means for again throwing the spindle into operation and maintaining it in operation after the spindle leaves the last-mentioned station, means for throwing the spindle out of operation after a cop has been wound, means for severing and fastening the thread when the spindle carrying the wound cop is at another station, and means for doffing the wound cop from the spindle when the spindle reaches still another station.
24. In a winding machine, the combination of 55 a turret, a plurality of winding heads carried by the turret, each winding head comprising a winding spindle and means associated with the winding spindle for presenting thread to the spindle and causing the thread to be wound on the spindle, means for throwing the thread winding spindle out of operation when a cop has been wound, and means for stopping rotation of the 60 turret when the winding head reaches a predetermined station in case a cop has not been completely wound on the spindle when it reaches said 65
- station, and manually controllable means for again throwing the turret into operation.
25. In a winding machine, the combination of a turret, a plurality of winding heads carried by the turret, each including a winding spindle, 5 means for intermittently rotating the turret to successively move each winding head to a plurality of stations, controllable driving means for the spindles, means acting automatically to control said driving means to throw the winding 10 spindle into operation temporarily while the winding head is at one of said stations, and means for controlling said driving means to throw the winding spindle into operation after it leaves said station and to maintain it in operation until a cop 15 has been wound on the spindle.
26. In a winding machine, the combination of thread winding devices including a winding spindle for cross winding thread on the spindle to form a cop, and means for indexing said winding 20 devices after the completion of the winding operation to locate the cop a definite point in the formation of the outer layer of the wind in a predetermined position, and a device cooperating with said positioning means for positioning the 25 stretch of thread extending from the cop in a predetermined position with relation to the peripheral surface of the cop.
27. In a winding machine, the combination of a winding spindle, a traverse guide cooperating 30 therewith to cross wind thread on the spindle to form a cop, driving connection between the traverse guide and the winding spindle whereby the winding spindle and traverse guide operate in timed relation, and means for indexing said traverse guide to locate a definite point in the formation of the outer layer of the wind in a predetermined position.
28. In a winding machine, the combination of thread winding devices including a winding spindle for cross winding thread on the spindle to form a cop, means for indexing said winding 35 devices after completion of the winding operation to locate the cop to position a definite point in the formation of the outer layer of the wind in a predetermined position, a device cooperating with said positioning means for positioning the stretch of thread 40 extending from the cop in a predetermined position with relation to the peripheral surface of the cop, and means for fastening the outer end of the wound thread of the cop while 45 the cop is in said position.
29. In a winding machine, the combination of thread winding devices for cross winding thread to form a cop to position a definite point in the 50 formation of the outer layer of the wind, and for locating the wound cop in a predetermined position, a device cooperating with said positioning means for positioning the stretch of thread extending from the cop in a predetermined position with relation to the peripheral surface of 55 the cop, and means for fastening the outer end of the wound thread to the cop including a tucking finger for tucking the end portion of the thread beneath the outer coils of the cross winding, the thread being first tucked beneath the last wound one of said coils.
30. In a winding machine, the combination of a winding spindle, a thread traverse guide for 60 cooperating with the winding spindle to cross wind thread on the spindle to form a cop, a tucking device movable in a plane substantially tangent to the periphery of the finished cop, and means to locate the cop to position a definite point in the formation of the last wound helical 65
- 70
- 75

3,100,370

coils of thread in a predetermined position with relation to the path of the thread tucking device.

31. In a winding machine, the combination of a turret, a plurality of winding heads carried by the turret, each including a winding spindle, means for intermittently rotating the turret to successively move the winding heads to a predetermined station, means cooperating with each spindle for cross winding thread on the spindle 10 to form a cop previously to the spindle reaching said station, and means for forming a loop in the thread extending from the cop and tucking the loop beneath portions of a plurality of the last cross wound coils.

32. In a winding machine, the combination of 15 winding devices for cross winding thread to form a cop comprising a winding spindle, means acting automatically after the completion of the winding for severing the thread, means for securing 20 the end of the wound thread to the wound thread mass while the thread mass is on the spindle, and means for temporarily holding the supply end of the thread preparatory to the winding of the next cop.

33. In a winding machine, the combination of 25 a winding head including a winding spindle, a device carried by the head for detachably holding the free end of the thread, means for removing the free end of the thread from said device and applying it to the spindle whereby when 30 the spindle is rotated the thread is wound on the spindle, and means acting automatically at the completion of the winding operation for severing the thread and for fastening the end of the 35 wound thread to the wound thread mass while the wound cop is on the spindle and for applying the supply end of the thread to said first-mentioned device preparatory to the next winding operation.

34. In a winding machine, the combination of 40 devices for cross-winding thread to form a Universal wound cop, means for forming a loop in the length of thread extending from the wound cop and a device cooperating with said means for positioning the loop beneath a plurality of adjacent cross-wound coils of an outer layer of coils, the loop having its apex directed inwardly from 45 the last wound coil of said adjacent coils.

35. A structure according to claim 34 in which 50 means is provided for severing the thread adjacent the outer end of said loop.

36. In a winding machine, the combination of 55 devices for cross-winding thread to form a Universal wound cop, and means including a tucking member working over the periphery of the cop for tucking a portion of the length of

thread extending from the wound cop beneath a plurality of adjacent cross-wound coils of an outer layer of coils, the thread being tucked first beneath the last wound coil of said adjacent coils and then the others successively, said tucking operation being in a direction tending to tighten the stretch of thread extending to said tucked in portion. 5

37. In a winding machine, the combination of 10 devices for cross-winding thread to form a Universal wound cop, a thread tucking member and a feeler connected to move together as a unit, means for operating said tucking member and feeler to cause the tucking member to be projected beneath a plurality of adjacent coils of 15 an outer layer of coils, said tucking member entering first beneath the outer wound coil of said adjacent coils and then the others successively, and means for presenting the length of thread 20 extending from the cop to the tucking member so as to cause the tucking member to tuck a portion of the thread beneath said adjacent coils during its movement beneath said coils, said feeler during said tucking movement of the tucking member riding over the surface of the adjacent 25 layer of underlying coils and serving as a guard to cause the tucking member to properly enter beneath said adjacent coils.

38. A structure according to claim 37 in which 30 the feeler and tucking member are pivotally mounted so as to permit the feeler to adjust itself to the surface of said underlying layer of coils.

39. In a winding machine, the combination of 35 winding devices for cross-winding thread to form a Universal wound cop comprising a winding spindle, a thread traverse guide, a device acting automatically after the completion of the winding to engage the stretch of thread extending from the wound thread mass to the traverse guide 40 at a point adjacent the thread mass and attach it to said mass while the thread mass is on the spindle, means for severing said stretch of thread in proximity to said point of attachment, and means for temporarily holding the supply end of 45 the thread preparatory to the winding of the next cop.

40. A structure according to claim 39 in which 50 said thread attaching device comprises a tucking finger which engages said stretch of thread at said point and tucks a portion thereof beneath a plurality of coils of an outer layer of coils of the wound thread mass. 55

DICKERSON G. BAKER. 55
DWIGHT R. GARDNER.

CERTIFICATE OF CORRECTION.

Patent N. 2,163,578.

June 27, 1939.

DICKERSON G. BAKER, ET AL.

It is hereby certified that error appears in the printed specification of the above numbered patent requiring correction as follows: Page 1, second column, line 46, for "Feb." read Fig.; page 2, second column, line 61, for "inrespective" read irrespective; page 6, first column, line 23, for the reference numeral "286" read 288; page 8, second column, line 20, for "adapt" read adjust; page 9, first column, line 19, for the reference numeral "84" read 584; same page, second column, line 10, for "69" read 60; page 12, second column, line 22, claim 26, after the word "cop" insert to position; lines 55 and 56, claim 29, strike out the words "to position a definite point in the formation of the outer layer of the wind" and insert the same after the word "cop" in line 57, same claim; and that the said Letters Patent should be read with this correction therein that the same may conform to the record of the case in the Patent Office.

Signed and sealed this 15th day of August, A. D. 1939.

(Seal)

Leslie Frazer
Acting Commissioner of Patents.
